UNITED STATES PATENT OFFICE.

WILBUR S. LEWIS, OF CLEVELAND, OHIO.

CRIMPER.

Application filed August 17, 1925, Serial No. 50,818. Renewed August 1, 1927.

This invention relates to crimpers, and more particularly to hand operated crimpers for crimping a deformable tube against an article of smaller diameter.

- 6 An object of my invention is to provide crimpers which are simple in construction and which can be readily applied and operated to crimp a deformable body annularly against an article of smaller diameter.
- 10 Another object of my invention is to provide crimpers having a pair of cooperating jaws which are formed with guide portions for folding and directing a deformable body toward an intermediate semi-circular portion during the crimping operation.
- 15 These and other objects will be apparent to those skilled in the art to which my invention relates, by reference to the accompanying drawings taken in connection with the following description.

In the drawings, Figure 1 is a plan view of a crimper in open position, embodying my invention; Fig. 2 is a similar view with the jaws in closed position upon an article; 25 and Fig. 3 is a side elevation of the crimper.

Referring now to the drawings by characters of reference, the crimper consists of a pair of elements 10 and 11, interposed intermediate their ends, and pivotally secured 30 together by a rivet 12. The handle portions 13 of the elements curve upwardly adjacent the pivotal connection and terminate in finger grips 14 at their ends.

The ends of the elements 10 and 11, opposite from the grips, provide jaws 15 which are formed with crimping faces at their inner adjacent edges. The end portions 16 of the crimping jaws are bent so that they will extend in reverse planes to that of the handle portions. Thus the jaw of the handle held uppermost will lie in a plane beneath the plane of the jaw of the handle held lowermost. The curve of the handles is also slightly different so that they will engage when the jaws are overlapping to limit the closing movement of the jaws. By varying the curve of the handles, their engagement will vary and thus the action of the jaws can be limited in their closing movement to provide the desired minimum crimping area.

The crimping faces of the jaws are similar in outline, and are oppositely disposed. The outer and inner portions 16 and 17 respectively of each crimping face are substantially straight and extend substantially

at acute angles to each other. The central portions 18 of the jaw faces, intermediate the straight angularly disposed ends, are substantially semi-circular in outline. 60

The ends of the jaws can be opened to be applied around a deformable article, such as a tube 19, and as the jaw ends are closed so that the distance intermediate is less than that of the tube, they will form an enclosed 65 crimping face. The straight face portions 16 and 17 will deform the tube, as the jaws are moved toward each other, and will guide the tube toward the curved portions of the jaws. The straight faces will crimp 70 or fold, the wall of the tube longitudinally, as the area therebetween is decreased. When the tube has been crimped by the straight faces to a diameter substantially 75 that of the area between the curved faces 18, further movement of the jaws toward each other will deform the crimped portion of the tube annularly.

The angle formed by the two face portions 17 is always sufficiently great that the 80 tube being crimped will not be pinched between these faces, but will be guided toward the curved faces 18 so that the shape of the final crimp produced will be determined by the latter. 85

One of the uses for which this invention is adapted is in connection with crimping tubes against a strand of hair in a permanent waving process. Such tubes are frequently formed of paper and sheet foil associated therewith, and it will be seen that a crimping action on such tubes will crimp the tube against a strand of hair 20, as illustrated in Fig. 2, so that it will be self secured and sealed therewith. 90 95

Various changes can be made in the structure described herein as an embodiment of my invention, without departing from the spirit of the invention and the scope of the appended claims. 100

What I claim is:—

1. A crimper comprising a pair of crossed elements, means for pivotally securing said elements together, handles at one end of said elements, and crimping jaws having jaw faces of similar outline at the other end of said elements, the inner edges of said jaws being opposed to provide a crimping surface and having substantially straight angularly disposed end portions joined by a rounded intermediate portion. 105

2. A crimper comprising a pair of crossed

- elements, means for pivotally securing said elements together, handles at one end of said elements, and crimping jaws having jaw faces of similar outline at the other end of said 5 elements, the inner edges of said jaws being opposed to provide a crimping surface and having substantially straight angularly disposed end portions joined by a rounded intermediate portion, the outer ends of said 10 jaws being bent to reverse their relation relative to that at the central portions of said elements.
3. A crimper comprising a pair of crossed elements, means for pivotally securing said 15 elements together, handles at one end of said elements, and crimping jaws having jaw faces of similar outline at the other end of said elements, the inner edges of said jaws being opposed to provide an enclosed crimping surface when in overlapping relation and having angularly disposed end portions joined 20

by arcuate intermediate portion, the outer ends of said jaws being bent to reverse their relation relative to that of the elements at their connection.

4. A tool for crimping tubular articles which comprises a pair of pliers, the opposing faces of which are each formed with a crimp-shaping section and guiding sections 25

30

35

guiding sections diverging therefrom, the opposed guiding sections forming relatively obtuse angles with one another as the pliers are closed.

In testimony whereof, I hereunto affix my signature.

WILBUR S. LEWIS.
